UNITED STATES PATENT OFFICE.

EARL F. HAUSERMAN, OF CLEVELAND HEIGHTS, EARL R. SMITH, OF LAKEWOOD, AND LEROY D. MOWERY, OF CLEVELAND, OHIO, ASSIGNORS TO THE E. F. HAUSERMAN COMPANY, OF CLEVELAND, OHIO, A CORPORATION OF OHIO.

SKYLIGHT STRUCTURE.

Application filed June 22, 1922. Serial No. 570,196.

To all whom it may concern:

Be it known that we, EARL F. HAUSERMAN, EARL R. SMITH, and LEROY D. MOWERY, citizens of the United States, residing at Cleveland Heights, Lakewood, and Cleveland, Ohio, respectively, have invented certain new and useful Improvements in Skylight Structures, of which the following is a specification, reference being had therein to the accompanying drawings.

This invention relates to skylight structure. One object of the invention is to provide a new and improved skylight structure adapted to prevent breakage of glass due primarily to unequal settling or racking of the supporting structure or building, such skylight structure comprising as important parts thereof a broad, substantially rigid bed for supporting the glass, and novel means for resiliently securing the glass and bed in assembled relation with each other and with the supporting members.

Another object is to construct a skylight structure wherein movement of the supporting members with respect to the glass carrying bed is permitted without imposing breaking strains directly on the glass. Another object is to provide a substantially rigid glass carrying bed secured to a supporting structure in a manner to permit relative movement of the said parts against the action of resilient means.

Another object is to provide a new and improved skylight structure having resilient glass securing means located within the interior thereof.

Another object is to construct as a unit a combined chair and resilient securing means for skylight structure.

Another object is to provide, in building construction, means for mounting exposed metal or glass parts on a supporting structure in a manner to effectually prevent leakage of water around the securing means or through the joints of the said parts.

Other objects will be pointed out in the following specification.

In skylight structures, of the general type illustrated herein and in use heretofore, considerable breakage of glass has been experienced due primarily, it is believed, to unequal settling or racking of the supporting structure or building. The glass has often been carried on a bed which was sub-

ject to bending or distortion with the settling or racking of the supporting structure or building, the result being, first, a drawing away of certain parts of the bed from the glass, leaving the glass to be carried on small and often isolated areas of the bed as compared with the initial large areas of support; and second, if the bending or distortion were sufficiently great, in throwing part of the bending force or the weight of the supporting structure on the glass. In other words the bed was not substantially rigid and usually followed the supporting structure in its settling or racking leaving the glass little or no support or even putting additional strain on it.

By this invention, however, the glass is carried on a substantially rigid bed which is not bent or distorted even although certain of its supports may be withdrawn, and which thus not only strongly resists any decrease of its initial, effective glass carrying area, but, should the bed supporting structure settle or in any other manner move away from the bed so as not to support it, the bed will carry the glass without imposing bending strains thereon. Relative movement of the bed and supporting structure are also resiliently resisted. Furthermore, the glass is resiliently secured to the bed and supporting structure by means which can be rendered substantially waterproof.

In the drawings attached to this specification and forming a part thereof.

Fig. 1, is a perspective view of the improved skylight structure showing the parts in assembled relation.

Fig. 2 is a vertical cross section taken through the chair shown in Fig. 1.

Fig. 3 is an enlarged view showing the relative position of the dome nut, bolt, and cap before the nut is screwed into final position.

Figs. 4 and 5 are respectively end and side elevations of the improved chair construction.

Fig. 6 shows in perspective a fragment of the cap provided with a flange surrounding the bolt holes.

Fig. 7 is a perspective view of an improved water proof packing strip.

Fig. 8 is an enlarged cross sectional view of the dome nut.

Fig. 9 shows in perspective a modified form of chair on a reduced scale.

In the drawings, wherein is shown one embodiment of our invention, 1 indicates a sheet metal channel or rafter adapted to span the opening in a roof or elsewhere which is to be provided with a skylight. Within the channel, 1, are secured a plurality of support or chairs, 3, each having side and bottom portions and being substantially U-shaped in transverse cross section with the closed or bottom end upward and the sides lying adjacent the sides of the channel, 1, and suitably secured thereto, as by a bolt, 4, and nut, 5.

The closed end, or portion, 6, of the U is restricted in width and is substantially flat to support therein a sheet metal bed, 7, having depending flanges, 10. From each side, 8, of the chair 3, tongues or projections 9, are struck outwardly to form seats for depending flanges 10, of bed 7. The bed is thus supported over a transverse distance equal approximately to the width of the bed, the latter having thus an enlarged area adapted to afford a wide support for glass plates 11, thereon. A tongue 12, is struck inwardly from one side 8, of the chair 3, to provide a seat upon which may rest a post or threaded bolt 13, the shank of which passes through aligned openings 14, in the bottom portion of chair 3, and bed 7. Opening 14, is formed substantially mid-way between the tongues 9, and thus permits bolts 13, to pass through the portion 6, of chair 3, and bed 7, at right angles thereto. A spring 15, encircling the shank and pressing against the head of bolt 13, tends to prevent upward or outward movement of the bolt with respect to the chair 3. The bed 7, by reason of its being formed with the depending flanges 10, is substantially rigid and adapted to effectively resist any forces tending to bend or distort it or to decrease the initial relatively broad, flat surface on which the glass rests.

It will be noted that the bolt, 13, is somewhat loosely mounted in the chair, 3, and in hole, 14, such mounting combined with the spring, 15, affording the necessary side play and vertical movement required to maintain the glass in contact with the bed 7, while permitting slight movement of the bed supporting structure relative thereto.

It will be noted further that the chair, 3, interposes no obstruction to the free passage of water along the channel 1. Although this invention aims to prevent leakage of water through the skylight, it frequently happens that water of condensation collects on the glass and is discharged into the channel where it may become mixed with dust, dirt, and similar refuse. When even slight obstructions are presented in the channel to the passage therealong of this water mix-

ture, there is the danger of rusting which is entirely overcome by this improved structure.

On either side of glass plates or panels, 11, strips, 16, of fibrous material are preferably employed to prevent contact of the glass with the metal, to cushion the glass on the metal and thus prevent breakage, and to act as waterproofing elements. Preferably these strips are rendered substantially impervious to water along their edges, as is indicated at 16a in Fig. 7, the width of such impenetrability being sufficient to be overlapped by the sheet metal cap 17. A convenient method of waterproofing these strips is by taking them in roll form and dipping the ends of the rolls into a bath of suitable liquid water-proofing material, each end of the roll being thus dipped and the strip then permitted to dry.

Sheet metal cap 17 is adapted to seat on the top packing strip 16, and may cover substantially the entire width thereof, perforations 18 being formed in this cap at suitable intervals to coincide with the bolts 13, which project therethrough. Preferably this cap is bowed or curved slightly so that when it is assembled with strips 16 the side edges will be forced into close fitting engagement with the upper strip and thus tend to form a watertight joint. Dome nuts 19 having tapped openings 20 engage with the threads on the bolts 13 and serve to draw the chair 3, bed 7, strips 16, and cap 17 into close engagement with each other and with the glass plates 11. By tightening nuts 19 on bolt 13, spring 15 may be put under considerable compression which, while holding the members in assembled relation as a unit, still permit sliding or shifting movement of the parts thereof to compensate for unequal settling or racking movement of the building or supporting structure.

Surrounding each perforation 18 is formed an upstanding flange 21 adapted to lie in fairly close contact with bolts 13, the flange being conveniently formed by extruding the metal around the perforation. The nut 19 is counter-sunk at 22 to engage flange 21 on the outside thereof, the counter-sunk surface being so inclined with respect to the flange that it engages with the flange before the nut engages elsewhere with cap 19. Further movement of the nut on the bolt forces the flange into close engagement with both the nut and bolt. In this manner tightening of the nut on the bolt results in a substantially water-tight joint with both the bolt and the nut and leakage of water about the bolt is thus prevented.

In Fig. 9 is shown a modified form of chair comprising forked legs or sides 25 to be secured to the channel 1, a hollow top portion 26 having outstanding projections

27 to support flanges 10 of bed 7. A bolt 13 and spring 15 may be retained in the interior of portion 26, the bolt projecting upwardly through a suitable hole 28 in the top 5 thereof.

Having now described this invention in sufficient detail for those skilled in the art to understand and practice the same, what is desired to secure by Letters Patent is defined in what is claimed, it being understood however, that various modifications may be made in the structure herein described without departing from the spirit and scope of the invention.

15 What is claimed is:

1. In a skylight structure in combination, a sheet metal channel, a metal chair secured therein, a substantially rigid sheet metal bed channel shaped in cross section seated on the 20 said chair with the open side down and having a flat top portion adapted to support glass plates, glass plates carried by the said bed, a sheet metal cap adapted to cover the edges of the said plates, a spring within the 25 said bed and a bolt extending upwardly through the said chair, bed and cap and cooperating with the spring for securing the said plates in assembled relation.

2. In a skylight structure, in combination, 30 a sheet metal channel, a metal chair secured therein and having portions projecting outwardly from the sides thereof, a substantially rigid sheet metal bed having a flat portion adapted to rest loosely on the said chair, 35 and provided with depending edges to seat on the said outstanding portions of the chair, a glass plate and packing strips on either side thereof supported by the said bed, a sheet metal cap adapted to rest upon one 40 of the said strips, and means for yieldingly maintaining the said cap and bed in assembled relation with said glass plate and packing strips, comprising a spring pressed bolt passing through the said bed and cap.

45 3. In a skylight structure in combination, a plurality of bed supporting members spaced apart, a sheet metal bed having a wide flat top surface and down turned side edges, the said bed being supported at a 50 plurality of points by each of a plurality of said bed supporting members, glass plates carried by the top surface of the said bed, and means carried within each said bed supporting members for resiliently maintaining the plates, bed and supporting members 55 in assembled relation.

4. In a skylight structure in combination, a plurality of bed supporting members spaced apart, each having a perforation in 60 its top portion, a sheet metal bed having a wide flat top surface and down turned side edges, the said bed being supported at a plurality of points by each of a plurality of said bed supporting members, glass plates carried by the top surface of the said bed,

and means comprising a spring pressed threaded member carried within each said bed supporting members and projecting through the said perforation for resiliently maintaining the plates, bed and supporting members in assembled relation.

5. In skylight structure, in combination, a metal chair having side and bottom portions, a hole through the bottom portion, a headed bolt, loosely mounted in the said 70 hole, a spring around the bolt and pressing against the bolt head and the chair, for withdrawing the bolt from the opening in the chair and a projection from one of the side portions of the chair for retaining the bolt and spring in assembled relation with said chair.

6. In a skylight structure, in combination, a substantially rigid sheet metal bed having 75 downturned edges, glass plates carried by the bed, a sheet metal cap carried by the plates and adapted to cover the edges of the plates above the said bed, and means for yieldingly maintaining the said bed and cap in assembled relation with the said 80 plates including a member passing through the said bed and cap, and a spring cooperating therewith, the spring being positioned between the downturned edges of the said bed.

7. In a skylight structure, in combination, 85 a bed having a flat top surface and downturned side edges, a plurality of bed supporting members engaging the under side of the said bed between the said downturned edges, glass plates carried by the said bed, a sheet metal cap carried by the said plates and adapted to cover the edges of the plates above the said bed, and means for holding the said bed and cap yieldingly in assembled relation with the said plates comprising a member passing through the said bed, 90 cap and bed supporting members and a spring cooperating with the said member and positioned within the bed supporting member between the downturned edges of the bed.

100 8. In building construction, in combination, a perforated cap member, a threaded member extending through a perforation in the said cap member, a flange around the said perforation and a member having a threaded opening the sides of the said opening being formed to engage the said threaded member and cause the flange to contact with the threaded member and with the outer side of the said flange, with liquid sealing contact.

105 9. In skylight structure, in combination, 120 a cap member provided with an opening therethrough, a flange formed about said opening a threaded member fixed with respect to the cap member extending into the said opening and in substantial contact with the said flange, and a tapped member having 125

a threaded opening formed to engage the threaded member and the outer side of the said flange whereby the flange is gripped with liquid sealing contact between the said 50
5 threaded member and the tapped member.

10. In skylight structure, in combination, a perforated cap member having a flange surrounding each perforation, a bolt extending through said perforation adjacent the 10
10 said flange and a dome nut for each bolt having a tapped opening for engagement with the said bolt, portions of the said tapped opening being counter-sunk whereby it is adapted to engage the outer side of a flange 15
15 and to press it into liquid sealing engagement with the said bolt.

11. In skylight structure, in combination, a water proof joint comprising a glass plate, fibrous material arranged on either side 20
20 thereof and having its edges substantially impervious to water, a member for supporting the said glass plate and fibrous material, a cap member resting on the glass plate and fibrous material, having a perforation with 25
25 an upstanding flange surrounding the same, a bolt extending through said perforation and adjacent to said flange, and a dome nut having a counter-sunk tapped opening and formed to hold said cap member, fibrous 30
30 material, glass plate, and supporting means therefor in assembled relation, the counter-sunk portion of the said nut being adapted to form a substantially water tight junction between the bolt and the said flange.

35. 12. In a skylight structure, a rafter, a support thereon having an aperture, a post resting on the support and having a shank portion extending through and slidable in said aperture, a spring on said shank portion retaining 40
40 said post and permitting upward yielding movement thereof, a glass supporting strip resting directly on said support, glass panels resting on said strip at each side of said post, a packing strip, a retaining strip pressing the packing strip against 45
45 the upper side of the said glass panels, the

packing and retaining strips having perforations engaging said post, and means engaging said post for securing said retaining strip. 50

13. In a skylight structure, a rafter, a support thereon, a post resting upon said support and slidably mounted therein to have upward yielding movement and provided at its upper side with a threaded extension, a glass supporting strip resting directly on said support, glass panels on said supporting strip at each side of said post, a packing strip perforated for the said post, a retaining strip pressing said packing strip against 55
55 the upper side of the glass panels and having a perforation engaging said post, and a threaded head engaging the threaded extension of said post and adapted to secure 60
60 said retaining strip thereon. 65

14. In a skylight structure, a channel rafter, an inverted U-shaped support received therein and having an aperture in its upper portion, a post resting on the support and having a shank portion extending 70
70 through and slidale in said aperture, a spring on said shank portion retaining said post and permitting upward yielding movement thereof, a glass supporting strip resting upon said support, glass panels resting on said supporting strip at each side of said post, a packing strip perforated for the said shank, a retaining strip pressing the packing strip against the said glass panels at 75
75 their upper side and having a perforation 80
80 engaging said post, and means engaging said post for securing said retaining strip, whereby said supporting strip, glass panels and retaining strip are supported directly from said support, and all of the elements last mentioned can as a whole have upward yielding movement away from said support. 85
85

In testimony whereof, we, hereunto affix our signatures.

EARL F. HAUSERMAN.
